UNITED STATES PATENT OFFICE.

CRAWFORD D. CHALFANT, OF THORNPOR, OHIO, ASSIGNOR OF ONE-HALF
TO F. LEE NORTON, OF RACINE, WISCONSIN.

ATTACHMENT FOR THRESHING-MACHINES.

SPECIFICATION forming part of Letters Patent No. 616,899, dated January 3, 1899.

Application filed January 14, 1898. Serial No. 666,679. (No model.)

To all whom it may concern:

Be it known that I, CRAWFORD D. CHALFANT, a citizen of the United States, residing at Thornport, in the county of Perry and State of Ohio, have invented certain new and useful Improvements in Attachments for Threshing-Machines; and I do hereby declare the following to be a full, clear, and exact description of the invention, such as will enable others skilled in the art to which it appertains to make and use the same.

My invention relates to threshing-machines; and it consists in an attachment for such machines which will take the tailings from the tailing-spout and rethresh them and return them to the cleaning devices without again intermingling them with the straw going through the machine.

It more particularly consists in certain details of construction and combinations of parts hereinafter more fully set forth in the descriptive part of this specification and the claims following, reference being had to the accompanying drawings, in which—

25 Figure 1 is an elevation of a threshing-machine with my invention attached thereto. Fig. 2 is a longitudinal vertical section of the same. Fig. 3 is a transverse vertical section. Fig. 4 is a partial vertical section of my device 30 made longitudinally of the machine. Fig. 5 is a like view taken transversely of the machine, and Fig. 6 is a horizontal section of the fan-casing and its eduction-tube.

The mechanism included in my improved 35 mechanism is all compactly arranged within a single inclosing structure or casing and is provided with attaching means whereby it can be readily attached to or removed from any one of the various forms of threshing-40 machines now in use. This mechanism consists of the elevator C, which has its lower end connected to the threshing-machine, so as to receive the tailings of the machine. This elevator carries the tailings up and delivers them to the rethreshing-cylinder D, 45 where the tailings are subjected to the action of said cylinder, and are then delivered to the fan E, which drives the same into the threshing-machine upon the grain table or floor or

analogous device, from whence they pass to 50 the cleaning devices of the threshing-machine. These devices (the elevator, the cylinder, its concave, and the fan) may be of any preferred form which will accomplish the results sought to be attained. The fan and 55 cylinder and concave are located in the main trunk A of the casing and the elevator is inclosed in the part B of the casing. This casing is provided with perforated ears b b a a, whereby the same can be secured by bolts to 60 the main body or framework of the threshing-machine.

The fan-casing is provided with the eduction or discharge spout e, as best shown in Fig. 6, and this spout extends through the 65 side of the machine a sufficient distance to insure that the grain coming within the action of the fan shall be deposited upon the grain table or floor and shall not fall between the same and the side of the machine. a' is 70 a deflecting-plate to carry the tailings discharged by the elevator upon the cylinder D, so that they will be carried by the same through the teeth of the concave a².

The central portion of the fan E is provided 75 with a deflector e' to deflect the grain from the center of the fan.

From the foregoing description the operation of the device will be apparent to any one skilled in the art to which it relates. 80

The ordinary method of treating the tailings is to carry the same by an elevator and discharge the same into the threshing-cylinder of the machine, from whence it is discharged along and intermixed with the straw 85 passing rearward from the threshing-cylinder. The tailings include unthreshed grain-heads and grain in a more or less imperfectly-cleaned condition, and the intermixing of the same with the straw not infrequently results 90 in a portion of the grain being carried over with the straw.

In order that the grain as it issues from the discharge-spout may not be carried beyond the grain table or floor by the force of the 95 blast of the fan E, I prefer to provide the inner end of the spout with a pivoted deflector e². A short arm attached to the said deflector

is connected with a rod e^3 and extends to the outside of the threshing-machine or to the outer side of the attachment where it is provided with a hand or wheel nut or other means 5 for adjustment.

What I claim, and desire to secure by Letters Patent, is—

1. An attachment for threshing-machines comprising among its members, an elevator 10 to receive the tailings from the threshing-machine, a threshing mechanism to receive the tailings from the elevator, a fan and discharge-tube to receive and discharge the re-threshed tailings upon the grain-table of the 15 threshing-machine, and means for detachably

connecting said attachment to a threshing-machine, substantially as described.

2. In a threshing-machine attachment, the combination with the elevator, the cylinder and concave, the deflector above the cylinder, 20 the fan, and an inclosing casing for said parts including a discharge-spout adapted to extend within the threshing-machine, substantially as described.

In testimony whereof I affix my signature 25 in presence of two witnesses.

CRAWFORD D. CHALFANT.
